ABSTRACT OF THE DISCLOSURE

This invention is concerned with a ready electrically operated selective display of a length of scroll material between two reels. The mechanism is simple and fool-proof and provides independent adjustments for take-up speed and for rewind speed. The arrangement is such that the drive mechanism for one direction of scroll movement in no sense interferes with that which may have been selected for the other direction.

My invention relates to a scroll-scanning device having particular application to an educational or teaching machine, and in particular for those devices employed by the teacher to check the corrections or comments of the student on an elongated scroll containing the student's work.

When teaching machines of the character indicated employ large scrolls of teaching and work-product material, it becomes burdensome for the teacher to manually manipulate the scroll in order to examine and evaluate the student's performance or the fidelity of the student's correction of his own answers, where the span between take-up and supply reels of the scroll may be of relatively short extent or, for example, as large as 30 inches; and it is also difficult or burdensome, in a case of a large scroll, to obtain ready access to a particular desired location along the length of the scroll for careful evaluation. No satisfactory device for handling the situation is known to applicant.

Accordingly, it is an object of the invention to provide an improved scroll examining or scanning device eliminating much of the manual manipulation otherwise required for the teacher.

It is a specific object to provide a scroll-scanning device including selectively operable electric controls for driving one to the exclusion of the other of two spaced scroll-supporting spindles between which an elongated length of scroll material is stretched for examination.

It is a general object to meet the foregoing objects with a structure which is inherently inexpensive, of simple construction, and fool-proof in operation.

Other objects and various further features of novelty and invention will be pointed out or will occur to those skilled in the art from a reading of the following specification in conjunction with the accompanying drawings. In said drawings which show, for illustrative purposes only, preferred forms of the invention:

FIG. 1 is a simplified view in perspective of a portable scroll-scanning device of the invention shown supported on a table ready for use, most of the mechanism being hidden by the external housing parts;

FIG. 2 is a schematic plan view of elements and mechanisms contained within the device of FIG. 1;

FIG. 3 is a simplified side view of the scroll-supporting layout in FIG. 2;

FIG. 4 is an enlarged fragmentary view taken generally at the plane 4—4 of FIG. 2;

FIG. 5 is a simplified view generally in the style of FIG. 2 but showing a fragment of the mechanism in order to illustrate a modification; and

FIG. 6 is a simplified fragmentary view of modified drive mechanism.

2

Briefly stated, the invention contemplates the spaced rotary support of take-up and supply (or pay-out) ends of a scroll with a substantial length of the scroll supported on an elongated flat observing platten or surface, and means for the simple electrically controlled manipulation of the scroll material so as to minimize the mechanical inconvenience of shifting from one region to another on the scroll for examination of its information content. In the forms to be described, independent drive mechanism is provided for each scroll spindle, and the arrangement is such that either one or the other (but not both) of the drive mechanisms is engaged, depending upon the selected operation of a single actuator mechanism. Provision is made for simple adjustment of scroll driving speed, dependent upon whether pay-out or rewind functions are involved.

Referring to FIG. 1 of the drawings, the invention is shown in application to a device which may be portable and contained within a simple elongated generally prismatic housing, having a base 10 to rest upon a table top and a normally fixed housing enclosure 11 to which movable housing enclosure 12 is hingedly related. The hinged part of the structure includes an elongated depressed or recessed region 14 having an opening or window work 15 through which a portion of scroll material 16 is directly accessible for reading or for the making of handwritten commentary. In the form shown, upstanding enlarged parts 17—18 of the hinged portion of the enclosure 12 constitute covers for pay-out and take-up reels 19—20 (FIGS. 2 and 3) for the scroll material 16.

As far as the operator is concerned, he is presented with but a single actuating switch 21 normally centrally positioned in a non-actuating situation and movable in one direction to determine forward movement of the scroll material 16 and in the opposite direction to determine reverse or rewind movement of the scroll material 16. The legends F and R in FIG. 1 suggest the selectively available positions. A speed-control adjustment for one of the directions of scroll movement is available by setting a manual knob 22 as will be more fully explained below,

In the form of FIGS. 2, 3 and 4, the mechanism contained within the housing of FIG. 1 includes spaced spindles 23—24, journaled in their respective bearings 26'—26 in fixed relation to the frame or base 10. It will be understood that the reels 19—20 are removably positionable on their respective spindles 23—24 in such manner as to be driven in rotation upon drive of their respective supporting spindles 23—24. The spindles 23—24 are located to position scroll material 16 in preferably flat horizontal adjacency to a supporting surface of platten 27 which in turn is fixed to or forms part of the base 10. Suitable guide means 28—29 adjacent each spindle may be frame-based as suggested at 30, in order to make sure that scroll material paid out from reel 19 lies flat over platten 27 for the entire stretch between guides 28—29; the length of this span may, for example, be in the order of two to three feet.

In accordance with the invention, independent drives are selectively available for each of the two spindles 23—24, and in the form of FIG. 2 these drives are duplicates of each other and employ separate motor means 32—32' independently associated with each of the two drive mechanisms. Drive is accomplished by edge-contact of a friction wheel at a selected radius against the radial face of a drive disc; in the case of the drive mechanism for the take-up spindle 24, this comprises a drive disc 33 available for co-action with a drive wheel 34, which may be rubber-tired, carried on a drive shaft 35 having universal-joint connection at 36 to the output of motor 32; joint 36 may be merely a short length of rubber tubing, snugly fitted at its ends to the motor-drive shaft and to

the shaft 35. In the form shown, the drive mechanism, comprising the motor 32 and extending to the drive wheel 34, is all carried by a slide 37 guided by means 38 forming part of the frame or base 10. This mechanism as a whole is adjustably positionable along the guide 38 by means of the knob 22 already identified, and knob 22 is shown adjusting the threaded engagement of rod 39 in a nut 40 on the slide 37. It will be appreciated that the longitudinal adjustment effected at 22 for slide 37 is operative to displace the axis of shaft 35 generally radially with respect to the spindle 24.

The drive mechanism further comprises movable bearing means 42 located between the drive wheel 34 and the universal-joint 36, and means including a solenoid or electromagnet 43 is operative on the bearing means 42 to urge drive wheel 34 into operative engagement with disc 33, whenever scroll take-up is desired. In the form shown, the bearing means 42 is simply a loose wrap-around of part of a strap or arm 42a of magnetic-flux conductive material, the other end of the arm being pivotally associated at 44 with the frame or base 10. Preferably, that part of the shaft 35 which is piloted on the bearing means 42 is nonmagnetic, as of brass, aluminum, wood, or the like.

The electromagnet 43 is frame-based and its armature or core so positioned in relation to magnetic flux-conducting material of the bearing means 42 that magnet actuation necessarily draws the friction wheel 34 into firm driving contact with its associated drive disc 33. Ordinarily, if the arm 42a has a generally vertical orientation, it will not be necessary to resort to any special measures to locate arm 42a in the absence of magnet excitation. However, to avoid too much looseness of parts, I show a frame-based stop 45 determining an outer limit of arm 42a and frame-based spring means 46 normally urging bearing means 42 away from magnet 43 with a force which is readily overcome whenever magnet 43 is actuated.

The parts of the drive mechanism for the other spindle 23 may be carried on a slide 37' generally similar to the slide 37 and, since the drive parts for spindle 23 correspond exactly to those already described for the take-up drive mechanism (spindle 22), they are merely indicated in the diagram by primed notation of the same reference numerals.

To complete the structure of FIG. 2, the single selector control 21 is seen to comprise an electric switch of the double-throw, single-pole variety having spring means 48 to determine the center or inoperative position. Excitation voltage is available from a self-contained source, such as battery 49, connected to the switch 21 and selectively actuatable, to engage contact 50 for the case of scroll take-up drive, or to engage contact 51 for the case of scroll-rewind drive. Battery voltage applied to motor 32 via contact 50 is shown adjusted by rheostat 52, and a similar rheostat 52' provides for similar adjustment of the rewind motor 32', these adjustments being made appropriate to the basic motor-drive speed desired for pay-out and rewind fuctions.

For the case of pay-out drive selection, contact closure at 50 also excites a preferably parallel circuit to solenoid or electromagnet 43, assuring that the drive wheel 34 will only be placed in driving relation with disc 33 at times when the motor 32 is also excited. Since the rewind mechanism comprises essentially the same relation of parts as has been described for take-up, it will be seen that neither one of the drive mechanisms opposes actuation of the other, and yet each is instantly available depending upon the selected drive direction.

In the arrangement of FIG. 5, similar parts have been given the same reference numerals; the basic difference is that although drive mechanisms for take-up and rewind may be said to be independent and independently adjustable, they nevertheless derive their torque from a single motor 55, having independent universal-joint connections

36-36' to the respective drive shafts. The electrical arrangement is such that, regardless of the position of selector switch 21, the motor 55 will be driven at a speed determined by setting of rheostat 56, but only the correct magnet 43 (for take-up) or 43' (for rewind) will be actuated while the motor is running; in the form shown, the selector switch is of the double-pole double-throw variety, so that magnet selection and motor excitation may be in parallel circuits.

Also in FIG. 5, independent radius adjustment is available for the respective drive wheels 57-57', but this is achieved by merely shifting the drive wheels while shifting no other part of the drive mechanism. Each drive wheel thus is effectively keyed to its associated shaft 58, as along a keyed or splined length thereof. Slide means 59, longitudinally guided at 60 with respect to the frame, includes forked elements between which the drive wheel 57 is piloted, and manually adjustable means 61 is externally accessible to determine the threaded engagement of rod 62 in the slide 59. Since the drive wheels 57-57' are the only parts of the speed-adjustment mechanism which are moved, it goes without saying that in FIG. 5 the solenoid and movable bearing structures 42-42' are referenced directly to the frame 10 rather than via any movable slide.

It will be appreciated that the term "motor means" which has been used in connection with elements 32-32' in FIG. 3, and 55 in FIG. 5, is generically descriptive of a motor alone or with reduction-gear mechanism, as necessary to produce desired torque and speed for the drive shaft. Also, in situations where adequate range of drive speed is available through control of the motor alone it may be desirable to employ bevel-gear drive mechanism, as suggested at 70-71 in FIG. 6, in place of the friction-wheel engagements described in connection with FIGS. 3 and 5. In the case of a gear drive 70-71, solenoid excitation will still be effective to achieve drive engagement to the desired spindle, depending on whether advance or rewind is indicated.

It will be seen that I have described a relatively simple device for selectively controlling the movement of scroll material 16 between widely spaced guides 28-29. Provision is made for independent control of motor speed and of drive-wheel-engagement radius for both the forward and rewind directions of movement. All parts are basically simple and fool-proof and may be of such lightweight construction as to make the device completely portable, employing battery power.

While I have described the invention in detail for the preferred forms illustrated, it will be understood that modifications may be made without departing from the spirit of the invention as defined in the claims which follow.

What is claimed is:

1. A scroll-scanning device, comprising a frame including an elongated platten having a support surface for scroll material, first and second scroll spindles journaled for rotation at fixed locations on said frame and at opposite longitudinal ends of said platten, means on one spindle for removably supporting a first scroll thereon, means on the other spindle for removably supporting a second scroll thereon, frame-based guide means adjacent each spindle for guiding scroll material payed from said first spindle to said second spindle via a supported and displayed length immediately overstanding said support surface, each spindle having a drive-receiving generally radial extending member; drive-motor means; first and second independent drive mechanism for said drive-receiving members, each drive mechanism including an elongated shaft having its own universal-joint connection to said motor means, a rotatable drive member carried by each shaft for edge-driving engagement with the adjacent drive-receiving member, separate movable outboard-bearing means supporting each shaft between its rotatable drive member and its universal-joint connection, said bearing means being each normally in non-driving relation with the associated drive disc, and selectively actuatable electromagnetic means for

moving a selected one of said bearing means to load its associated drive element into edge-engagement with the associated drive-receiving member; said last-defined means also including means exciting said motor means only during periods of excitation of said solenoid.

2. The device of claim 1, in which separate electromagnetic means are provided independently associated with each movable bearing means, said selectively actuatable means determining the selected one of said electromagnetic means for operation at any given time.

3. The device of claim 1, in which said motor means comprises separate motors, one for each drive shaft and in which said selectively actuatable means determine the excitation of one to the exclusion of the other of said motors.

4. The device of claim 1, in which each of said drive-receiving members is a generally radially extending disc, and each of said rotatable drive members is a friction wheel.

5. The device of claim 4, in which said first drive mechanism is mounted on a slide guided for displacement with respect to said frame and along an axis such as to displace the associated drive shaft axis generally radially with respect to the associated drive-disc axis, and manually operated adjusting means determining the sliding displacement position of said slide, whereby radius of drive-wheel contact with its associated drive disc is adjustably variable.

6. The device according to claim 4, in which a separate drive motor is associated with each universal-joint and in which each drive mechanism including its motor is mounted on a separate slide guided with respect to said frame on a longitudinal displacement axis such as to displace the associated drive-shaft axis generally radially with respect to the associated spindle axis, and independent adjustably variable positioning means for each of said slides, whereby the radial location of drive-wheel engagement with the associated drive disc for each of said drive mechanisms may be independently variable.

7. The device of claim 1, in which said movable bearing means includes an element of magnetic flux-conducting material hingedly related to said frame on a hinged

axis offset from the associated shaft axis, and in which the associated electromagnetic means includes a magnetic core closely spaced with relation to the magnetic material of said bearing means.

8. The device of claim 7, in which spring means normally urges said bearing means in a direction opposed to that determined by electromagnetic actuation, and in which a frame-based stop limits displacement of said bearing means in response to spring actuation.

9. The device according to claim 4, in which said drive-motor means comprises a single motor to which the shafts of said drive mechanisms are independently connected through said universal-joint connections, and in which one of said shafts includes an elongated keyed region over which its drive wheel may be longitudinally displaced while maintaining non-rotating association therewith, and adjustably positionably locating means for said displaceable drive wheel along its shaft.

10. The device of claim 9, in which the drive wheel for the other drive mechanism is also slidable along and keyed against rotation with respect to its shaft, and further adjustable locating means for selectively positioning the drive wheel of said other drive mechanism along its shaft.

11. The device of claim 1, in which each of said drive-receiving members is a first bevel-gear element, and each of said rotatable drive members is a second bevel-gear element, said gear elements being poised for engagement upon actuated movement of the associated bearing means.
